UNITED STATES PATENT OFFICE.

GEORGE A. MOORE, OF MEDFORD, MASSACHUSETTS.

SUNDIAL.

Application filed June 25, 1927. Serial No. 201,365.

The object of this invention is the construction of an improved sun dial designed to be carried in the pocket and to be of very low cost, and adapted to be used in different sections of the United States. In carrying my invention into effect, I make the body of the device from sheet material, preferably cardboard, with differing dials on the opposite sides, and a small compass adapted to be shifted from side to side; the compass being provided with means for adjusting its zero point to suit different locations in the same general section of the country.

In the drawings forming part of this specification, Fig. 1 is a plan view of a sun dial embodying my improvements. Fig. 2 is a cross section on the line 2—2 in Fig. 1. Fig. 3 is a face view of the compass. Fig. 4 is a face view of mica shield and adjusting device. Fig. 5 is a face view of the card-body alone, showing the opposite side to that in Fig. 1. Fig. 6 shows the two stiles superposed.

As shown in Figs. 1 and 5, the card 1 is of convenient size to enter a vest pocket, and bears upon each side a representation of a watch 2 having the usual hour-spacings and figures. Through the card below the center of the watch is a hole 3 beneath which is located the compass 4 which is retained in place by means of studs 5 projecting from ears 6, the studs being pressed in through holes 7 in the card. To make room for the compass in the lower portion of the watch-face, the hour-spacings are all located between the hole 3 and the noon hour.

The stile 10 is located on the card with its lowest point close to the compass, and is attached to the card by a metal strap 11 riveted at 12 to the card and having a socket 13 engaging a slot 14 in the stile to permit of folding the latter against the card. Rivets 18 in the card above and below the strap 11 beneath the hinged edge of the stile 10 serve to retain the latter in its right-angle position.

Markings 15 radiating from the lower end of the stile to the hour-spaces serve to render the shadow-line cast by the stile more clearly read.

The compass is covered by means of a mica disk 16 provided with perforated ears 17 matching the ears 6 of the compass and designed to be penetrated by the studs 5. As shown in Figs. 2 and 4, a second mica disk 19 is rotatably mounted on the disk 16, by a rivet 20, and is given one or more holes 21 for permitting it to be readily turned, as by a pencil point or tooth-pick. These holes are designating points, by means of which to adjust the dial to different localities. In doing this, the device is held horizontally in the sun shine at some known hour and turned until the shadow of the stile strikes that hour. If the compass needle is not pointing toward the noon hour of the watch-face, as it seldom does, the disk 19 is carefully turned until its line 22 corresponds with the needle. The sun dial is then in condition for measurably accurate determination of all hours of sun shine by turning the card until the marking 22 is parallel with the needle.

What I claim as my invention is:

1. A sun dial comprising a card having suitable markings upon both sides, stiles on both sides, and a compass adapted to be attached to each side, said card having an opening through which to observe the compass needle.

2. A sun dial as set forth in claim 1, wherein the compass has lateral ears each provided with a stud, the card having perforation adapted to frictionally receive said studs, for holding the compass beneath said opening.

3. A sun dial comprising a card having dial markings upon each surface, a stile attached to each side, each stile being substantially triangular and differing from the other in shadow-casting angle, a compass, and means whereby it can be attached to either side of the card in order to be used in connection with either stile.

In testimony that I claim the foregoing invention, I have hereunto set my hand this 23rd day of June, 1927.

GEORGE A. MOORE.
